(57) **CLAIM**

The ornamental design for a vehicle parking indicator sensor, as shown and described.

DESCRIPTION

FIG. 1 is front view of an ornamental design for a vehicle parking indicator sensor.

FIG. 2 is a top view of the vehicle parking indicator sensor of FIG. 1.

FIG. 3 is a bottom view thereof; and,

FIG. 4 is a side view thereof, wherein the opposite side is substantially a mirror image thereof.

The broken lines shown in the figures are for illustrative purposes only and forms no part of the claimed design.
